UNITED STATES PATENT OFFICE

GEORGE W. NELSON, OF CLEVELAND, OHIO, ASSIGNOR TO THE STEWART MACHINE COMPANY, OF ELYRIA, OHIO, A CORPORATION OF OHIO; ARTHUR J. CURREN TRUSTEE OF SAID THE STEWART MACHINE COMPANY, DEFUNCT

COIN-CONTROLLING MECHANISM

Application filed June 28, 1926. Serial No. 119,021.

My invention relates to new and useful improvements for coin control mechanisms adaptable for use in co-operation with vending machines.

5 An object of my invention is to provide an improved coin control mechanism adapted to function in co-operation with a delivery mechanism of a vending machine which is simple in construction and positive 10 and effective in its co-operation with the same.

Another object of my invention is to provide an improved adjustable coin control mechanism which may be controlled by predetermined 15 various numbers and values of coins to permit the adaptability of my mechanism to the vending of articles of varying value.

Another object of my invention is to provide 20 an improved mechanism of the class stated in which a coin slot permits the insertion of coins of a certain predetermined value only and in which perfect registering alignment of the coin or coin receiving slot-ways is assured.

Another object of my invention is to provide 25 a coin controlled mechanism composed of relatively few parts and not complicated in operation, and in which the parts are durable in construction and assembled together in a substantial manner.

The above and other objects of my invention will be apparent from the following 30 description and drawings wherein one embodiment of my invention is illustrated.

Fig. 1 is a front elevation of my vending machine;

Fig. 2 is a side elevation of the same 40 showing a closure member partially open;

Fig. 3 is a view similar to Fig. 2 showing the closure in closed position;

Fig. 4 is a view similar to Fig. 1 with a portion cut away to show my coin control mechanism in position;

Fig. 5 is a detail view of a handle and lever control for the coin control mechanism;

Fig. 6 is a detail view of an adjusting pin for various numbers and kinds of coin used to operate the machine;

Fig. 7 is a side elevation of my coin control mechanism substantially the size of my apparatus used in practice, in normal locked position;

Fig. 8 is a fragmentary view of a portion 55 of my coin control mechanism, in unlocked position;

Fig. 9 is a view similar to Fig. 8 of another portion of my coin control mechanism;

Fig. 10 is a front elevation of my coin 60 control mechanism;

Fig. 11 is a rear elevational view of my coin control mechanism;

Fig. 12 is a view similar to Fig. 8, showing the coins in position and the carriage at 65 the bottom of its stroke;

Fig. 13 is a detail view of a lock lever;

Fig. 14 is a detail view of a coin ejector lever;

Fig. 15 is a detail view of a pawl reversing lever;

Fig. 16 is a side elevation of the same;

Fig. 17 is a detail view of a double acting pawl;

Fig. 18 is a plan view of a coin channel broken in the center; and

Fig. 19 is a side elevation of the same.

Referring more particularly to the drawings my vending machine, preferably, comprises a sheet metal rectangular receptacle 1, fastened together in any suitable manner by rivet or screws 2. A portion of the front wall being cut away to enable a person authorized to have easy access to the interior of 85 the receptacle 1.

Hinged at 4 to the receptacle 1 is a closure member 3, which is angular in vertical cross section and disposed in a manner with relation to the receptacle 1 so as to cover the 90 cut-away portion in the front wall of the receptacle 1, and also to cover the top of the receptacle 1 (Fig. 3). The front wall of the closure 3 is provided with an opening 6 forming a window therein and having a pane 95 of glass 7 secured therein in any suitable manner whereby the respective purchaser is enabled to know at a glance whether there are any articles in the machine to be vended, before inserting a coin. The closure is also 100

made of sheet metal parts held together by rivets 5 or the like.

On the top of the closure 3 at the rear is disposed a conventional lock 8, the bolt of which engages and is retained by a keeper plate secured to the rear walls of the receptacle 1. In this manner access to the interior of the receptacle may only be possible to those authorized, for removing the coins deposited therein, or for replenishing the receptacle with a new supply of articles to be vended.

My vending machine may be operated by any predetermined number or kinds of coins. The coin control mechanism forming the subject matter of this application is provided with suitable adjusting means which will be hereinafter more fully described.

The coin control mechanism operating means comprises a spring retracted handle 9 provided with a suitable grip portion 10 and pivoted at 11 to the side wall of the receptacle 1. Disposed adjacent the grip portion of the handle 9 is a pair of guide members 12, secured to the side wall of the receptacle 1, preferably, by means of bolts 13 and 13' in spaced relation to each other. The bolts also function as limit stops for the downward and upward movement of the handle 9.

Secured to the inner front wall of the closure 3 are a pair of lugs 14 provided with suitable pins 15, which pins engage slots 17 on the arm 16 supporting the closure in its two adjusted positions, for either removing the coins from the receptacle, or for operating suitable mechanism more fully described in my co-pending application filed concurrently herewith, Serial No. 119,020 for arranging the vending apparatus for proper reception of a new supply of articles to be vended. The top portion of the closure 3 projects beyond the rear wall of the receptacle, and is curved downwardly at 18 to prevent rain or the like from entering the receptacle. One of the side walls of the closure is provided with a coin slot 19 which registers with a coin slot 20 in the receptacle 1, for the reception of any desired number or kinds of coins for setting the coin control mechanism in position for the actuation of the handle 9, thereby enabling the lever controls which will now be described to be unlocked.

Secured in any suitable manner to an eccentric 11' on the pivot 11, and disposed on the inside of the receptacle, at 22 is a spring retracted operating lever 23 for operating the coin control mechanism 27 through the agency of the vertical link 25, pivoted at its lower end to the operating lever 23 near the outer end thereof at 24, the upper end of which is detachably secured to a headed stud 26 carried by the carriage 33 of the coin control mechanism.

The coin control mechanism which will now be described is secured preferably in the

upper right front of the receptacle 1 adjacent to coin slots 20 and 19 and to the rear of a flange formed in the front end of the side wall of the receptacle and designated by the numeral 80.

Depending from the operating lever 23 at substantially the center thereof is a link 94 which is connected with a vending mechanism which is fully described in my co-pending application filed the same date as this application and covering a vending machine. By depressing the handle 9 in a downward direction the operating lever 23 will impart a pull in a downward direction on the link 25, and when coins are inserted into the slot 19 and 20 the coin control mechanism will operate in a manner which will hereinafter be more fully described.

The coin control mechanism is preferably mounted in a base plate 27 formed substantially channel shaped in cross section, one end thereof being bent upwardly at right angle to form a side wall 28. Opposite the side wall 28 and arranged in spaced relation thereto is an angle shaped rack bar supporting member 29 secured to the base plate 27 preferably by means of screws, and provided with an overhanging rack 30 provided with a series of flattened rack teeth. Adjacent the two ends of the rack bar are two cut away depressed surfaces 31, one adjacent the lower end of the rack bar 30, the other being adjacent the upper end thereof. Disposed to the right and substantially in the center from top to bottom of the upper depression 31 of the rack bar 30 is a pin 34 secured in the rack bar 30 and projecting therefrom. A pin 34' is secured to the rack bar 30 in vertical alignment with the pin 34 below the same and disposed two teeth above the lower depressed portion 31 of the rack bar.

Carried adjacent to the upper end of the rack bar support 29 is an adjusting pin or spring 32 which may be secured to the rack bar support 29 preferably by a bolt, one end thereof projecting laterally with respect to the rack bar support 29 and having its end bent down to form a finger adapted to engage a slot 35 on a rotary adjustment 36. The adjustment 36 is adapted to be rotated upon a suitable bearing journaled to the base plate 27 and capable of varying the upward stroke of the carriage 33 according to the various numbers or kinds of coins. This adjustment operates in connection with the adjusting pin 71 which will be more thoroughly described in another portion of this specification. The adjustment member 36 is provided with suitable indicating marks.

A portion of the periphery of the rotary adjustment member 36 is cut away to form oppositely disposed flattened surfaces 37 and 38 having the suitable indications adjacent

the flat surfaces. The flattened surfaces 37 and 38 are spaced different distances from the axis of rotation of the adjustment member 36, the surface 37 being a greater distance from the axis than the surface 38, thus when the rotary adjustment member is rotated to present the surface 37 for the carriage 33 to strike against the upward movement of the carriage is relatively great and the coin controlled mechanism is set for pennies as shown in the Fig. 7 of the drawings. When it is desired to operate the machine on nickels the adjustment is rotated presenting the opposite flat face 38 for the carriage 33 to strike against, the movement of the carriage being relatively short.

A carriage 33, heretofore referred to, preferably rectangular in shape is mounted in the trackway formed by the side wall 28 and the rack bar support 29 and adapted to slide on the base plate 27 and held therein by means of the projecting rack bar 30. The upper end of the carriage is adapted to abut against the rotary adjustment 36, heretofore described, in any one of the adjusted positions, to vary the length of its stroke. Adjacent to the upper end of the carriage is secured the lug 26 which as heretofore stated is connected with the link 25 of the operating means heretofore described.

Pivoted to the upper portion of the carriage, at 40, adjacent the lug 26 is a double acting crescent shaped ratchet pawl 39 adapted to exert its action both in the downward travel of the carriage and in the upper travel of the carriage. As shown in Fig. 7 of the drawing, the pawl is in normal position and ready for the downward stroke of the carriage. The pawl 39 is provided with two pawl teeth 41 and 41' and adapted to swing on the headed pivot stud 40. Journaled on the same shaft with the double acting pawl 39 is a spring pressed pawl reversing lever 42 provided with a pair of extensions 43 and 44 arranged at substantially right angles to each other, and preferably stamped out of sheet metal. The horizontally disposed extension 43 engages the lugs 34 and 34' in a manner which will hereinafter be described, when the carriage is reciprocated its full stroke upwardly and downwardly. The depending arm 44 of the pawl reversing lever 42 is formed with bevel faces 45, at its end, adapted to snap over a cam surface 46 on the carriage. A coil spring 47 disposed between the head of the stud 40 and the lever 42 presses the reversing lever with the pawl 41 to cause the bevel faces 45 of arm 44 to snap over the cam surface 46 when forced over neutral position on top of the cam surface 46.

Pivoted to the carriage adjacent the center thereof at 48, is a dog releasing and coin ejecting lever 49 provided with an integral upstanding hooked shaped portion 50 which

is adapted to swing the lever 49 on its pivot when the carriage is moved downwardly thereby engaging the beveled end of the hook portion 50 of the lever 49 with the coin or coins 51. An upstanding lug 55 is engaged by the lever 49 to limit its engagement with the coin channel 65. The downwardly extending portion 52 of the lever 49 engages a lug 53 carried by the lock lever 54, the lock lever being pivoted on the same point with the lever 49. The lateral projection 56 of the lock lever is provided with an upstanding lug 57 to which one end of a coil spring 58 is secured. The opposite end of the coil spring is secured to a pin 59 carried on the carriage. The lock lever 54 is cut away to provide space for the pin. The downwardly extending portion 60 of the lock lever 54 is hooked toward the rack bar 30. The hooked shaped portion 60 slides in the lower depressed portion 31 of the rack bar 30 and engages the lower end of the depressed portion 31 at 61 to prevent a full stroke of the carriage 33, and a subsequent operation of the vending mechanism, when the proper coin have not been inserted into the coin control mechanism.

A coin channel 65 is secured to the side wall 28 of the base plate and extends downwardly from a point above the coin slot 70 (Fig. 6) in the base plate and is provided near the upper extremity with a coin slot 62. Secured to the side plate 28 is a flat spring 63 which extends downwardly and having a bent in portion 64 which is sprung into a suitable opening provided in the coin channel 65 adjacent to coin slot 62, and is adapted to force the coin 51 into the coin chute 67 on the upward stroke of the carriage by acting in co-operation with the coin ejector lever 49.

The coin adjustment heretofore referred to, for varying the number and kinds of coin to be used as desired in my machine, comprises a plate 68 (Figs. 6 and 10) secured to the side wall of the base plate having its outer portion 69 bent up and spaced from the wall to form a guideway 90 for the reception of preferably a wire adjusting pin 71 adapted to be slid into various adjustments in its guideway. The pin 71 is bent to form a head portion 72 and the opposite end of the pin is bent at right angles to form a hook 73 which engages a series of holes 74 in the side plate arranged in pairs, one pair above the other. The upper hole of each series is for adjustment for the lower denomination of coins.

The upper end of the carriage is extended at 75 to form a cover plate for the coin slot 70 when the carriage is in its down most position to prevent more coins being inserted into the coin slot until one article is vended.

Having thus described various parts of

my invention the operation of these parts is as follows:

Assuming the machine to be in normal position as shown in Figs. 1 and 7, with articles to be vended placed in their proper position in the receptacle, a coin or coins are inserted through the slots 20 and 70. The coins will drop in the coin channel 65 resting upon the hooked shape portion 73 of pin 71, projecting through one of the holes 74 (Fig. 12) in the side wall of the main frame of the coin control mechanism. The handle is now depressed by the operator which in turn forces the operating lever 23 downwardly, and link 25 connected thereto and fastened to the lug 26 of the carriage causes the carriage 33 to move downward a predetermined distance, depending on the number of coins inserted, to a point where the lever 49 engages one of the coins and is caused to ride over the outer faces of as many of the coins as are disposed within the channel 65, and is thereby caused to swing in the counter-clockwise direction on its pivots as best shown in Fig. 8. The lower end of the lever 49 engages the pin 53 on the lock lever 54 and swings the same on its pivot 48 against the tension of the spring 58 releasing the hook end 60 of the lock lever clear of the projection 61 of the rack bar and permitting the carriage 33 to continue its free and full stroke downwardly.

Upon downward movement of the carriage 33, if a coin has been inserted in the channel 65, the end 50 of the lever 49 will ride up on the coin, and the lever will be rotated about its pivot. This, by engagement of the portion 52 with the lug 53 will rotate the lever 54 moving the end 60 thereof away from the projection 61 on the rack bar 30. Full down stroke movement of the carriage 33 is thereby permitted if there is a coin or coins in the channel, but if there are no coins present the end 50 of the lever 49 will enter into the coin channel through an opening provided therein as particularly shown in Fig. 9, thus preventing the removal of the end 60 of the lever 54 from the projection 61, as described.

The double acting pawl 39 is in the position shown in Fig. 7 at the start of the downward travel of the carriage. As the carriage moves downward, the pawl tooth 41 of the crescent shaped double acting pawl engages the first tooth of the rack bar 30 which rocks the pawl and the lever 42 clockwise into the position shown in Fig. 8, with the tooth 41 ratcheting over the teeth of the rack 30 to prevent premature reverse movement of the carriage and with the bevel face 45 of the lever 42 pressed against the cam surface 46, the engagement of the faces 45 and 46 preventing accidental engagement of the other pawl tooth 41' with the rack teeth. Near the end of the downward move-

ment of the carriage 33, the extension 43 of the lever 42 strikes the lower pin 34' on the rack bar, whereby as the carriage continues its downward movement to the limit, the lever 42 is snapped over the cam face 46 and the lower pawl tooth 41' is brought into engagement with the rack bar as shown in Fig. 12. Downward movement of the carriage 33 may be stopped by the engagement of the tooth 41' with the projection 61 on the rack bar.

Upon upward movement of the carriage, the pawl tooth 41' will trail over the rack teeth and prevent immature downward movement of the carriage before it has reached its upper limit and at or adjacent the top of its stroke, the extension 43 on the lever 42 will engage the pin 34 and snap the lever 42 back to its original position.

Coiled about the headed pin 40 and exerting a spring action on the lever 42 is a coil spring 47 for snapping the depending arm 44 and its bevel face 45 over the cam surface 46.

When the operator releases his grip on the handle the article will have been delivered to him, at 77 (Fig. 1), and the automatic return means starts the carriage 33 in its upward movement to normal position.

This automatic return means comprises a spring 111 attached to the bar 23 as shown in Fig. 5.

It will be seen by referring to Fig. 12 the coins are held in the coin channel 65 by the pin 71 during the entire down stroke of the carriage 33. The carriage 33 having now started its upward travel the hook shape portion 50 of the coin ejector lever 49 comes in contact with the coins 51 (Fig. 9) in the coin channel and pushes them upward where they are engaged by the spring hook 64 and forced into the coin chute 67 where they fall by gravity into the coin box 95.

The carriage continues its upward movement until the spring 58 snaps the hooked lock lever 54 into the lower depression 31, the lever 49 having returned to normal position against its stop lug 55 after the same had passed the coins in the coin channel during the downward stroke.

When the lock lever 54 has been snapped into its locked position as shown in Fig. 7 of the drawings, the lateral extension 43 of the spring pressed lever 42 has struck the upper pin 34 swinging the depending arm 44 and its bevel face over the cam surface 46 thereby reversing the crescent shape double acting pawl 39 into position shown in Fig. 7 of the drawing, wherein the upper pawl rests against the upper depressed portion 31 of the rack bar. The coin control mechanism is now in normal locked position ready for the reception of coin and for the

operation of the handle to deliver another article.

Referring more particularly to Fig. 18 of the drawing, the coin channel 65 is more clearly illustrated and a better understanding of the same may be had by reference to this figure. 66 is the slot portion adapted to receive the inturned portion 64 of spring 62 to engage a coin as heretofore described. The slot 66, it will be seen, is formed in the channel forming flange 79 of the coin channel 65. A longitudinal slot 78 running substantially the entire length of the coin channel 65 which is adapted to provide a trackway for the hooked portion 50 of the coin ejector lever 49 heretofore described. The ends of the coin channel 65 are closed preferably by means of plates 81 which are secured in place in any suitable manner such as by bolts 82 engaging suitable opening 83. The bolts 82 also function to hold the coin channel assembled on the side wall 28.

Having thus described my invention in a single embodiment, I am aware that numerous and extensive departures may be made from the embodiment herein illustrated and described but without departing from the spirit of my invention.

What I claim is:

1. In a coin controlled mechanism for vending machines, in combination with a vending machine having a downwardly extending coin chute therein, an element having a slideway associated with the chute, provided with a coin inlet opening at an upper portion thereof, a carriage adapted to be reciprocated in the slideway, a lever, connecting means between the lever and carriage whereby movement of the lever in opposite directions may reciprocate the carriage, mechanical means actuated by movement of the lever to vend articles contained in the machine, an obstruction element adapted to be projected into the chute at a preselected point therein to limit the downward movement of coins placed in the chute, a detent means associated with the carriage to limit its downward movement to a predetermined amount, a trip lever for said detent means, said trip lever being mounted for movement with the carriage and operable at a predetermined position of the carriage by engagement of the trip lever with coins in the chute to trip said detent, said obstruction element being adjustable to a plurality of selective positions longitudinally of the chute whereby the number and character of coins required to effect tripping of the trip lever may be selectively varied.
2. In a coin controlled mechanism for vending machines, in combination with a vending machine having a downwardly extending coin chute therein, an element having a slideway associated with the chute, provided with a coin inlet opening at an

upper portion thereof, a carriage adapted to be reciprocated in the slideway, a lever, connecting means between the lever and carriage whereby movement of the lever in opposite directions may reciprocate the carriage, mechanical means actuated by movement of the lever to vend articles contained in the machine, an obstruction element adapted to be projected into the chute at a preselected point therein to limit the downward movement of coins placed in the chute, a detent means associated with the carriage to limit its downward movement to a predetermined amount, a trip lever for said detent means, said trip lever being mounted for movement with the carriage and operable at a predetermined position of the carriage by engagement of the trip lever with coins in the chute to trip said detent, said carriage slideway element and chute being disposed entirely within the casing of the vending machine, said coin inlet opening having a communicating passage in alignment therewith through a wall of the machine casing.

3. In a coin controlled mechanism for vending machines, in combination with a vending machine having a downwardly extending coin chute therein provided with a coin inlet opening at an upper portion thereof, an element having a slideway associated with the chute, a carriage adapted to be reciprocated in the slideway, mechanical means for reciprocating the carriage, a lever connected with the carriage and movable in correspondence with the movement thereof, article dispensing means actuated by movement of the lever to vend articles placed in the machine, an obstruction element adapted to be projected at a preselected point into the chute to limit the downward movement of coins placed therein, detent means for said carriage to prevent its downward movement, a trip lever for said detent means, said trip lever being mounted for movement with the carriage and operable by engagement thereof with coins in the chute to trip said detent and permit movement of the carriage, a stationary rack bar, a pawl on the carriage adapted to ratchet on the rack to prevent the return of the carriage before full downward movement of the same is effected.

4. In a coin controlled mechanism for vending machines, in combination with a vending machine having a downwardly extending coin chute therein, provided with a coin inlet opening in an upper portion thereof, an element having a slideway associated with the chute, a carriage adapted to slide vertically in the slideway, an obstruction element adapted to limit the downward movement of coins placed in the chute, detent means for said carriage to prevent its downward movement in the slideway, a trip

70

75

115

120

125

130

lever for said detent means, said trip lever being mounted for movement with the carriage and operable by engaging the coins in the chute to trip said detent, said obstruction comprising a pin adapted to be adjustably projected into the chute at a plurality of selective operative positions longitudinally of the chute, whereby the number and character of coins required to effect tripping of the trip lever may be varied in a predetermined manner.

5. In a coin controlled mechanism for vending machines, in combination with a vending machine, a handle for effecting ejection of articles to be vended from the machine, a coin controlled plunger element reciprocable under the control of the handle, a slideway element having guiding surfaces to guide the movement of said plunger element, a toothed rack carried by one of said elements adjacent the other element, a pivoted double pawl carried by the element other than that which carries the rack adapted for engagement with the rack, said pawl comprising a pair of joined pawl teeth, said teeth being oppositely disposed with regard to the pivot for ratcheting in different directions on the rack, an arm extending from the pawl, a projection carried by said other element than that which carries the rack, said arm being adapted to be sprung over the projection to position the pawl with one of its pawl teeth out of engagement with the rack and the other tooth engaged therewith, and 35 pawl-engaging means carried by the rack supporting element adapted to engage the pawl upon predetermined movements of the plunger element in either direction to effect pivoting of the pawl into alternate positions 40 to alternately engage its teeth with the rack.

6. In a coin controlled mechanism for vending machines, a reciprocable carriage, an element providing a slideway on which the carriage may be reciprocated, a coin chute having a coin inlet opening at an upper portion thereof for the reception of coins disposed adjacent said slideway and extending substantially parallel thereto, an obstruction element adapted to be projected 45 at a predetermined point into the chute to limit the downward movement of coins placed therein, detent means for said carriage to prevent its downward movement, a trip lever for said detent means mounted for 50 movement with the carriage and engageable with coins in the chute to trip said detent, a mechanism casing, a hand lever for the mechanism outside of the casing, an arm within the casing connected to the lever and 55 60 to the carriage whereby movement of the lever may force the carriage in a downward direction.

In testimony whereof I hereunto affix my signature this 25th day of June 1926.

GEORGE W. NELSON.
